A. E. L. SECQUEVILLE,
BONNET FRAME FOR AUTOMOBILE VEHICLES,
APPLICATION FILED JUNE 17, 1920.

1,420,292.

Patented June 20, 1922.

Inventor:

Alfred E. L. Secqueville
By Lawrence Langner
Attorney

UNITED STATES PATENT OFFICE.

ALFRED ERNEST LEON SECQUEVILLE, OF SEINE, FRANCE, ASSIGNOR TO SOCIETE ANONYME DES ANCIENS ETABLISSEMENTS SECQUEVILLE AND HOYAU, OF GENNEVILLIERS, SEINE, FRANCE.

BONNET FRAME FOR AUTOMOBILE VEHICLES.

1,420,292.

Specification of Letters Patent. Patented June 20, 1922.

Application filed June 17, 1920. Serial No. 389,715.

To all whom it may concern:

Be it known that I, ALFRED ERNEST LEON SECQUEVILLE, a citizen of the French Republic, and residing at Seine, France, have invented certain new and useful Improvements 5 in Bonnet Frames for Automobile Vehicles, of which the following is a specification.

The present invention has for its subject 10 a metal frame for the bonnets or hoods of automobile vehicles, this frame at the same time forming a lamp bracket. It has the following characteristics:—

Each frame is provided with a bracket 15 which may be cast integrally therewith and adapted to carry a lamp, lantern or other light, while on the inner edge of the frame is formed a groove to which the hood may be hooked, bolt guides also cast therewith, being arranged in suitable places relatively to this 20 groove. The outer edge of the frame is provided with a border, also cast therewith and adapted for securing the sides of the mud-guard. The cross section of the frame is such that the conduits for the light (electric 25 or acetylene) may be disposed therein and protected. Finally the frame extends up to the main chassis with which it is in alignment.

The frame with a lamp bracket cast in a 30 single piece thus constructed constitutes an entirely new article of manufacture.

In the accompanying drawing:

Figure 1 is a plan of the frame.

Figure 2 is a longitudinal section.

Figure 3 is a section on the line A—B of 35 Figure 1, and showing a fragmentary portion of a mud-guard bolted to the edge of the frame.

Figure 4 is a section on the line C—D of 40 Figure 1.

Figure 5 is a section on the line E—F of Figure 2.

Figure 6 is a section on the line I—J of 45 Figure 1, and showing a fragmentary portion of the hood or bonnet operatively engaged with the frame and also showing the location of the light cables in the groove in the frame.

Figure 7 is a section on the line G—H of 50 Figure 5.

In the drawings, 1 is the body of the frame cast in a single piece of aluminium or other suitable metal. On this frame is

cast at the foundry an arm or bracket 2 adapted to support the light. The mounting 55 of the light is thus facilitated and the inconvenience connected with light supports assembled by means of bolts, which soon become loose and consequently put the lights out of order and renders the attachment 60 noisy, is avoided.

Along the whole inner edge 3 of the frame is a mortise groove 4 in which is adapted to engage the rim 7 of the hood or bonnet 11 which is held in position by spring bolts 5 65 as indicated in Figure 6. Each bolt terminates in a head which is pushed back automatically when the bonnet is lowered into the groove and then engages behind the rim of the bonnet when it will be effectively held in 70 the groove. The bolts 5 are mounted in cylindrical guides or bushes 6 cast on the inner edge of the frame. No movement can thus be produced in the engagement of the hood which consequently remains quite silent during 75 the working of the vehicle. Again it will be seen that with this arrangement the opening and closing of the bonnet can be effected to a certain extent automatically without trouble by the simple operation of 80 a handle which may be provided at any suitable position on the bonnet.

The frame 1 overlies and is secured to the longitudinal side beam of the chassis by bolts (not shown). It extends rearwardly 85 from the front cross-beam of the chassis to approximately the middle of the side beam and gradually decreases in width from its front end to its rear extremity, the latter being rounded off as indicated at 8 in Figure 1 to merge with the side beam.

The frame 1 is provided in its under surface with a longitudinal groove 13 which overlies the side beam of the chassis and receives and houses the light cables 12, as indicated in Figure 6. At its outer edge the frame 1 is provided with a flange 14 to which the mud-guard 15 is attached by bolts 16 as indicated in Figure 3.

It will be understood that the arm 2 instead of being cast may be supported upon the frame and secured thereto by rivets for example. In this construction although less advantageous, the frame still serves as light carrier.

Having thus described my invention what

I claim as new and desire to secure by Letters Patent is:—

1. A bonnet frame for automobile vehicles, comprising a frame with a groove therein for the reception of the bonnet rim, and a light bracket secured to said frame.
2. A bonnet frame comprising a frame with a groove therein for the reception of the bonnet rim, guides on said frame, spring bolts mounted in said frame, and a light bracket on said frame, the frame, guides and light bracket being cast in one piece.
3. A bonnet frame comprising a frame with a groove therein for the reception of the bonnet rim, the said frame being of a cross

section to receive the conduits for lighting purposes, guides on said frame, spring bolts mounted in said frame, and a light bracket on said frame, the frame, guides and light bracket being cast in one piece.

4. A bonnet frame comprising a frame with a groove therein for the reception of the bonnet rim, the said frame being of a section to engage with and fit around the longitudinal beam of the chassis and the apron, guides on said frame, spring bolts mounted in said frame, and a light bracket on said frame, the frame, guides and light bracket being cast in one piece.

ALFRED ERNEST LEON SECQUEVILLE.
